Primary Examiner — R. Johnson(74) *Attorney, Agent, or Firm* — John H. Thomas, P.C.(57) **CLAIM**

The ornamental design for a box drum, as shown and described.

DESCRIPTION

FIG. 1 is a perspective view of a box drum according to the design;

FIG. 2 is a front view of the box drum of FIG. 1;

FIG. 3 is a side view of the box drum of FIG. 1. The right side view, left side view and back view of the box drum of FIG. 1 are the same;

FIG. 4 is a top view of the box drum of FIG. 1;

FIG. 5 is a bottom view of the box drum of FIG. 1;

FIG. 6 is a perspective view of a second embodiment of a box drum according to the design;

FIG. 7 is a front view of the box drum of FIG. 6;

FIG. 8 is a side view of the box drum of FIG. 6. The right side view, left side view and back view of the box drum of FIG. 6 are the same;

FIG. 9 is a top view of the box drum of FIG. 6; and,

FIG. 10 is a bottom view of the box drum of FIG. 6. The broken lines in the Figures illustrate box drum features that form no part of the claimed design.
